DESIGN FOR A LICENSE TAG TRIM MEMBER

Jacob F. Martin, Bellevue, Ohio

Application July 11, 1936, Serial No. 63,787

Term of patent 3½ years

To all whom it may concern:

Be it known that I, Jacob F. Martin, a citizen of the United States of America, residing at Bellevue, Huron County, Ohio, have invented a new, original, and ornamental Design for a License Tag Trim Member, of which the following is a specification, reference being had to the accompanying drawing, forming part thereof:

Fig. 1 is a front elevation of the license tag trim

member embodying my new design; and

Fig. 2 is a view on the line II—II, Fig. 1.

The sectional view in Fig. 2 shows the clip in dotted lines which is merely a thin strip of the conventional type.

I claim:

The ornamental design for a license tag trim member substantially as shown and described.

JACOB F. MARTIN.
